UNITED STATES PATENT OFFICE.

CHARLES S. SPITZER AND JOHN GLOUB, OF CHICAGO, ILLINOIS.

SOUND BOX.

Application filed May 2, 1921. Serial No. 466,084.

To all whom it may concern:

Be it known that we, CHARLES S. SPITZER and JOHN GLOUB, both citizens of the United States, and residents of Chicago, in the county of Cook and State of Illinois, have invented certain new and useful Improvements in Sound Boxes, of which the following is a full, clear and exact description.

The invention relates to sound boxes. The object of the invention is to provide a sound-box by which sound will be reproduced in an improved manner.

The invention consists in the several novel features hereinafter set forth and more particularly defined by claim at the conclusion hereof.

In the drawings: Fig. 1 is a side elevation of an instrument embodying the invention. Fig. 2 is a section taken on line 2—2 of Fig. 1. Fig. 3 is a section taken on line 3—3 of Fig. 1. Fig. 4 is a detail of the case showing the sound conduit therein.

The invention is exemplified in a sound-box comprising a case 5 which is preferably formed of a natural sea-shell and is secured by one or more screws 6 to a metallic member 7 which is connected by a screw-thread 8 to a tone-arm 9, which may be of any suitable construction. A diaphragm 10 is held between rings 11 in a channelled ring 12, which is screw-threaded to the case and secures the diaphragm and rings 11 operatively in the case 5. A needle 13 in a holder 14, which is pivotally supported on a bracket 15, is operatively connected to the center of the diaphragm by an arm 16, as well understood in the art. The diaphragm is spaced from the inner face of the case 5 so as to form a sound-chamber 17. The tone-arm 9 is provided with a conduit 18 which forms a sound-connection for the case and through which the sound will pass to the usual amplifier.

A characteristic of the invention is that the case is provided with a helicoidal sound-conduit 20 between the chamber and the tone-arm which has been found, in practice, to reproduce the sound from the diaphragm in an improved manner. The conduit 20 is flared away from the central portion of the case and, commencing at 21, progressively increases in depth, so that it extends under a wall-portion 22 of the case which extends over the sound-outlet 23, and the opening 23' in the attaching member 7. The entirely surrounded portion 24 of the conduit adjacent the outlet 23 is gradually constricted from the chamber 17 to the outlet 23 which is off-center relatively to the center of the case. In practice, it has been found that a case constructed of natural sea-shell and having a conduit of the conformation shown will reproduce the sounds in an improved manner.

The invention is not to be understood as restricted to the details set forth, since these may be modified within the scope of the appended claim, without departing from the spirit and scope of the invention.

Having thus described the invention, what we claim as new and desire to secure by Letters Patent, is:

In a sound-box, the combination of a case, a diaphragm at one side of and forming a chamber in the case, and a tone arm at its other side, the case being formed with a helicoidal sound-conduit therein between said chamber and said connection, said sound-conduit on the diaphragm side being substantially coextensive in area with said diaphragm and being progressively constricted toward said tone arm.

CHARLES S. SPITZER.
JOHN GLOUB.
